(57) **CLAIM**

The ornamental design for a bottle, as shown and described.

DESCRIPTION

FIG. 1 is a top front right side perspective view of the bottle with the left side view being symmetrical to the right side view;

FIG. 2 is a rear elevational view of the bottle of FIG. 1; FIG. 3 is a top plan view of the bottle of FIG. 1; and, FIG. 4 is a bottom plan view of the bottle of FIG. 1 showing finger grip indentations.

The broken line showing of the environment is for illustrative purpose only and forms no part of the claimed design.

1 Claim, 2 Drawing Sheets
